PROCESS AND APPARATUS FOR PRODUCING LOW
BOILING POINT HYDROCARBON OILS
Original Filed May 17, 1920

UNITED STATES PATENT OFFICE

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR PRODUCING LOW BOILING POINT HYDROCARBON OILS

Original application filed May 17, 1920, Serial No. 381,922. Renewed April 24, 1928. Divided and this application filed May 5, 1923. Serial No. 636,860.

My invention relates to improvements in a process and apparatus for producing lower boiling point hydrocarbon oils and refers more particularly to a process in which the character of the distillate is controlled by regulation of the dephlegmating temperature.

This application is a division of an original application filed by me under date of 10 May 17, 1920, Serial No. 381,922.

Among its salient objects are to provide a process in which the temperature of the dephlegmating or condensing agent is controlled so that either a large or a small percentage of the vapors released from the oil body are condensed in passing therethrough; to provide a process in which the temperature of the successive stages of dephlegmation may be varied so that the oil vapors 15 may be treated to produce the greatest possible yield, a more uniform distillate, or so treated that any particular cut or fraction 20 may be extracted from the oil without necessitating the redistilling of the distillate 25 cured; to provide an apparatus for the carrying out of this process and in general to provide an apparatus of the character referred to.

The single figure is a diagrammatic side 30 elevation of the apparatus with parts in section.

In cracking hydrocarbon oils, after the disintegration of the molecules in the reacting chamber, the distillate which is produced by the condensation of these oil vapors is produced in an inverse relation to the way in which they are cracked, that is, with the heating of the oil, the low boiling point hydrocarbons will first be released from the 35 oil body, subsequently as the temperature is increased, the higher boiling point hydrocarbons will come off. So, with the cooling of the vapors, the high boiling point oils will first be condensed and subsequently as 40 the temperature is decreased, low boiling point vapors will be liquefied. From this it will be seen that the method and means of cooling or condensing the oil vapors is of as much importance as the heating there- 45 of. By the controlling of the temperature 50 of. By the controlling of the temperature

at which the condensation takes place, the character of the distillate may be controlled. The controlling of this condensing temperature is the most important function of the following process:

Referring in detail to the drawing, the raw oil is introduced from any convenient source to the dephlegmator 1 through the inlet pipe 2, which is regulated by valve 3. The raw oil, together with condensate con- 55 densed in the dephlegmator, collects in vertically arranged pools 4, 5 and 6, the levels of which are controlled by standpipes 6a, which convey the surplus oil from each pool to the pool below. The oil, after dephleg- 60 mating the oil vapors which bubble up through the pools by means of risers 7, collects in the bottom of the dephlegmator and is drawn off through the line 8, which is controlled by valve 9. This oil containing 65 what condensate it may collect in dephleg- 70 mating the vapors is charged to the heating coils 10 through the pump 11, charging pipe 12, controlled by valve 13. The heating coils are mounted above the furnace 14, which 75 is heated by any suitable means (not shown). The heated oil, after being raised to a crack- 80 ing temperature, is directed to the reacting or vapor chamber 15 through the pipe 16 which is regulated by a valve at 17.

One or more of these vapor chambers may be interposed in the system according to the quantity of oil to be treated. The vapor chamber shown at 15 is equipped with pyrometer 18, pressure gauge 19 and removable 85 cleaning plates 20. A residuum drawoff 21 controlled by valve 22, furnishes a means for removing the heavy residual oil, together with the precipitated carbon collect- 90 ing in the vapor chamber. The vapors re- 95 leased from the oil body are directed through the risers 23 to the line 24 by means of which they are introduced to the bottom of the dephlegmator. As explained, the vapors rise through the successive pools 95 through the risers 7 bubbling up through the raw oil in each pool and what vapors are not condensed in these successive pools are drawn off through the gooseneck 25, which is controlled by valve 26. These vapors, 100

after being subjected to the cooling effect of the water condenser 27, collect as a distillate in the receiving tank 28. This receiving tank is equipped with pressure gauge 5 29, liquid level gauge 30, liquid drawoff 31, controlled by a valve 32, and a gas relief pipe 33, controlled by valve 34. The water condenser 27 is fitted with a water inlet pipe 35 and an outlet pipe 36.

10 If it is desired to decrease the temperature of the liquid oil contained in either of the pools 4, 5 and 6, the same may be drawn off through the lines 37 and forced by the pumps 38 through coils in tanks 39 which 15 are cooled by water, from which it is directed back to the respective pools by means of the return lines 40. It is essential that the valves 41 and 42 are open during this local circulation and that the valves 43 and 20 44 are closed. If, on the other hand, for any reason it is more desirable to raise the temperature in any one of these pools, the liquid oil is similarly drawn off through the pipes 37 and directed down through the lines 25 37a, and circulated by means of the pumps 45 through the heating coils 46 mounted above suitable heating means 47, after which the heated oil proceeds back to the respective pools through the return lines 48 and 30 49 through a short connecting section of the return lines 40. It is essential during this circulation that the valves 43 and 44 are in an open position and the valves 41 and 42 are closed.

35 In this manner, when it is desired to obtain a distillate containing only the more volatile hydrocarbons such as the naphtha and benzine content, the temperatures of the pools must be lowered so that the high 40 boiling point hydrocarbons will be condensed therein, the lighter or more volatile oil vapors bubbling through the successive pools and finally condensed as low boiling point distillate in the receiver 28. Thus, by 45 controlling the temperature of the dephlegmating agent, the quantity and character of the distillate finally collected in the receiver may be positively controlled.

I claim as my invention:

50 1. A process for producing low boiling point hydrocarbon oils, consisting in cracking the oil in heating and reacting zones, dephlegmating the oil vapors by intimately intermingling them with the incoming raw 55 oil in a series of pools, increasing the temperature of the oil in the respective pools to decrease the condensation therein by locally circulating the same from said pools through heating means and back to the respective pools.

2. A process for producing low boiling point hydrocarbon oils, consisting in cracking the oil in heating and reaction zones, dephlegmating the oil vapors by intimately 65 intermingling them with the incoming raw

oil in a plurality of pools, separately controlling the condensation in the dephlegmating stage by increasing the temperature of the oil in the respective pools by local extraneous circulations from said pools through heating means and back to the respective pools. 70

3. A process for producing low boiling point hydrocarbon oils, consisting in cracking the oil in heating and reacting zones, 75 dephlegmating the oil vapors by causing the same to bubble up through successive pools of the incoming raw oil, controlling the temperature of the raw oil in the pools by locally circulating the oil from the respective pools separately through extraneous heaters and back to the respective pools. 80

4. In an apparatus for producing low boiling point hydrocarbon oils, the combination with means for cracking the oil, of a 85 dephlegmator comprising a plurality of superimposed compartments in which the incoming raw oil collects in pools, means for causing the cracked vapors to bubble through the oil in said pools, separate heating means connected with the respective pools for raising the temperature of the oil therein, and means for locally circulating the raw oil from said pools through said heating means and back to the respective 90 pools. 95
